CLAIM

The ornamental design for a toy flying vehicle, as shown and described.

DESCRIPTION

FIG. 1 is a perspective view from above, to the front and to the right side of the new design for a toy flying vehicle; FIG. 2 is a perspective view from above, to the rear and to the left side thereof;

FIG. 3 is a perspective view from below, to the front and to the left side thereof;

FIG. 4 is a perspective view from below, to the rear and to the left side thereof;

FIG. 5 is a right side view thereof;

FIG. 6 is a left side view thereof;

FIG. 7 is a top plan view thereof;

FIG. 8 is a bottom plan view thereof;

FIG. 9 is a front view thereof; and,

FIG. 10 is a rear view thereof.

In the drawings, the broken lines are for the purpose of illustrating portions of the article that form no part of the claim.

1 Claim, 7 Drawing Sheets
